CLAIM

The ornamental design for a speaker housing and stand, as shown and described.

DESCRIPTION

FIG. 1 is a front perspective view of the speaker housing and stand;

FIG. 2 is a rear perspective thereof;

FIG. 3 is a front elevation view thereof;

FIG. 4 is a rear elevation view thereof;

FIG. 5 is a right elevation view thereof, the left elevation view being the mirror image of FIG. 5;

FIG. 6 is a top plan view thereof;

FIG. 7 is a bottom plan view thereof;

FIG. 8 is a front perspective view of the speaker housing and stand according to another embodiment;

FIG. 9 is a rear perspective view of the embodiment of FIG. 8;

FIG. 10 is a front elevation view of the embodiment of FIG. 8;

FIG. 11 is a rear elevation view of the embodiment of FIG. 8;

FIG. 12 is a right elevation view of the embodiment of FIG. 8, the left elevation view being the mirror image of FIG. 12;

FIG. 13 is a top plan view of the embodiment of FIG. 8; and, FIG. 14 is a bottom plan view of the embodiment of FIG. 8.

The dotted lines showing portions of a speaker housing and stand are provided for the purpose of illustrating environment and form no part of the claimed design.
